KNIFE SHARPENING ATTACHMENT FOR AN ELECTRIC MIXER OR THE LIKE

Donald E. Leman, Chicago, Ill., assignor to Sunbeam Corporation, Chicago, Ill., a corporation of Illinois

Application January 19, 1959, Serial No. 54,226

Term of patent 14 years

(Cl. D37—1)

Fig. 1 is a front perspective view of the knife sharpening attachment for an electric mixer or the like, showing my new design;

Fig. 2 is a front elevational view thereof;

Fig. 3 is an elevational view thereof as seen from the left of Fig. 2;

Fig. 4 is an elevational view thereof as seen from the right of Fig. 2;

Fig. 5 is a rear elevational view thereof; and

Fig. 6 is a top plan view thereof.

I claim:

The ornamental design for a knife sharpening attachment for an electric mixer or the like, substantially as shown.
